TREATMENT OF HYDROCARBONS

Louis Schmerling and Vladimir N. Ipatieff, Chicago, Ill., assignors to Universal Oil Products Company, Chicago, Ill., a corporation of Delaware

No Drawing. Application July 6, 1942,
Serial No. 449,946

16 Claims. (Cl. 260—683.4)

1

This invention relates to the treatment of iso-paraffinic hydrocarbons to produce therefrom branched chain paraffinic hydrocarbons of higher molecular weight. In a more specific sense, this invention is concerned with a novel process for interacting alkylatable paraffinic hydrocarbons, herein termed isoparaffinic hydrocarbons, with alkyl esters of chloroformic acid to produce higher boiling paraffinic hydrocarbons of gasoline boiling range.

In one specific embodiment, the present invention relates to a process for synthesizing hydrocarbons which comprises reacting an isoparaffinic hydrocarbon with an alkyl chloroformate under alkylating conditions in the presence of a Friedel-Crafts type metal halide catalyst.

Considerable quantities of butanes, pentanes, and other paraffinic hydrocarbons of relatively low molecular weights are available in the relatively light hydrocarbon material condensable from natural gas and usually referred to as casing head gasoline. These relatively light components of casing head gasoline also include certain amounts of the corresponding isoparaffins, namely, isobutane, isopentane, etc. The relatively low boiling normal paraffins may also be isomerized into the corresponding isoparaffins by suitable treatment. Further quantities of butanes and pentanes are formed as by-products in the cracking of petroleum fractions and of other hydrocarbon oils to produce gasoline.

Alkyl esters of chloroformic acid which are utilized as alkylating agents in the process of the present invention have the general formula: C_1COOR , in which R represents an alkyl group. Alkyl chloroformates are readily obtainable by the treatment of an alcohol with phosgene. Thus, as indicated in the following equation, reaction of 1 molecule of phosgene with 1 molecule of isopropyl alcohol results in the formation of 1 molecule each of isopropyl chloroformate and hydrogen chloride:

Some of the alkyl chloroformates which are often referred to as alkyl chlorocarbonates have

2 the respective boiling points which are listed as follows:

	Alkyl ester of chloroformic acid	Boiling pt., °C.	@ mm. pressure
Methyl	71-74	760	
Ethyl	92-94	760	
Isopropyl	53-54	160	
n-Propyl	113-115	760	
n-Butyl	140-145	760	
Isobutyl	38-39	28	
n-Amyl	60-62	15	
Isamyl	60-62	20	
n-Hexyl	62-65	10	

15 Friedel-Crafts type metal halides which are utilized as catalysts for promoting the alkylation of an isoparaffin with an alkyl chloroformate in accordance with the present invention include such salts as aluminum chloride, aluminum bromide, zinc chloride, zirconium chloride, ferric chloride, antimony chloride, bismuth chloride, and others. We prefer, however, to employ aluminum chloride as the Friedel-Crafts type catalyst in such alkylation reactions because it is usually higher in catalytic activity than are other Friedel-Crafts type metal halides in a given reaction under specified conditions. Aluminum chloride may be used as such, may be supported by a refractory carrier such as alumina, silica, porcelain, etc., or it may be used in solution in a solvent such as a nitroparaffin, particularly nitromethane. Other Friedel-Crafts type metal halides and particularly chlorides may be added to the aluminum chloride or to its solution for the purpose of modifying the activity of the aluminum chloride.

20 25 30 35 40 While alkylation of isoparaffinic hydrocarbons by alkyl chloroformates may be effected in the presence of aluminum chloride and other Friedel-Crafts type catalysts at a temperature of from about -20° to about 100° C., the use of a temperature of from about 10° to about 70° C. is preferred. Pressures utilizable in the process may vary from substantially atmospheric to about 50 atmospheres or more. In order to obtain high yields of hydrocarbon products of gasoline boiling range with relatively small amounts of undesirable side reactions, such as polymerization, formation of organic compounds containing chlorine, etc., it is desirable to maintain a molar excess of isoparaffin hydrocarbon to alkyl chloro-

formate throughout the entire reaction period. Generally from about 2 to 25 molecular proportions of isoparaffinic hydrocarbons should be present per molecular proportion of alkyl chloroformate introduced to an alkylation reaction mixture in order to form a substantially saturated hydrocarbon material and to avoid undesirable polymerization and decomposition reactions.

The reactions which occur during the treatment of an isoparaffinic hydrocarbon with an alkyl chloroformate in the presence of a Friedel-Crafts type metal halide, or mixture of said metal halides, apparently involve the combination of the isobutane with the ester of chloroformic acid accompanied by splitting out of carbon dioxide and hydrogen chloride as illustrated by the following equation:

The use of chloroformates (or chlorocarbonates as they are often called) has the advantage over the similar use of other esters in that no free organic acid is produced during such reaction. Accordingly, the aluminum chloride used as catalyst in the process does not form an aluminum chloride-organic acid complex, and hence only catalytic and not stoichiometric amounts of aluminum chloride are necessary for the reaction.

Although the mechanisms of the reactions involved are not understood completely and should not be construed to limit the scope of the invention, the interaction, for example, of isobutane with isopropyl chloroformate yields heptanes which include 2,2,3-trimethylbutane, generally known as triptane. Heptanes so formed may react further with an additional quantity of the alkyl chloroformate such as isopropyl chloroformate to form a paraffin hydrocarbon of still higher molecular weight such as a decane. Decanes and other hydrocarbons of relatively high molecular weight may undergo decomposition and further conversion reactions in the presence of the catalyst to produce lower and higher boiling hydrocarbons which are generally paraffinic in nature.

The process of the present invention may be carried out either in batch or continuous types of operation. In batch type operation, the preferred procedure is to agitate a mixture of paraffinic hydrocarbon and catalyst at the chosen operating temperature and pressure and to introduce gradually thereto an alkyl chloroformate or a mixture comprising essentially an alkyl chloroformate and an isoparaffinic hydrocarbon or an isoparaffinic hydrocarbon fraction. After a time of mixing sufficient to effect substantially complete reaction of the alkyl chloroformate with the isoparaffin, the isoparaffin being present in excess of the alkyl chloroformate at all times, the agitation is stopped and the reaction mixture is separated into used catalyst, unconverted isoparaffin, alkylation product, and a mixture of hydrogen chloride and carbon dioxide, the latter two materials resulting from the decomposition of the alkyl chloroformate. The recovered catalyst and excess of unconverted isoparaffin may be utilized in a subsequent alkylation treatment. Sometimes hydrogen chloride is added to the reaction mixture, said hydrogen chloride either being introduced from an outside source or recovered from a previous alkylation run.

The process may be made continuous by pro-

viding a mixing zone through which the reacting organic compounds and catalyst are passed under alkylation conditions and in which sufficient time is given for the completion of the desired isoparaffin alkylation. The products from such a reaction zone are then directed to a separating zone in which the alkylation products are separated from the unconverted isoparaffinic hydrocarbon, catalyst, and a mixture of hydrogen chloride and carbon dioxide. The recovered unconverted isoparaffinic hydrocarbon and catalyst are then recycled to contact with the mixture of isoparaffinic hydrocarbon and alkyl chloroformate being charged to the process. Hydrogen chloride may also be recycled if desired.

The activity of the Friedel-Crafts type catalyst employed in the process is dependent upon the particular metal halide or metal halide mixture so utilized. The different Friedel-Crafts type metal halide mixtures which may be employed to catalyze the alkylation are not necessarily equivalent in their action particularly when reacting different isoparaffins with various alkyl chloroformates having alkyl groups of increasing carbon chain length and degree of branching.

The following examples are given to illustrate the character of the results obtained by the use of the present process, although the data presented are not introduced with the intention of unduly limiting the generally broad scope of the invention.

EXAMPLE I

Alkylation of isobutane by ethyl chloroformate was carried out by charging to a rotatable autoclave (lined with glass or nickel) a mixture of the isobutane, ethyl chloroformate, and catalyst in the amounts indicated in Table I.

Table I.—Alkylation of isobutane with ethyl chloroformate

	Run number			
	1	2	3	4
Reactants, g.:				
Ethyl chloroformate	110	110	50	110
Isobutane	172	168	81	172
Aluminum chloride	40	40	20	40
Autoclave lining		Nickel	Glass	Nickel
Pressure, atm.:				
Initial, nitrogen added	2	14	30	7
Maximum	4	18	50	25
Final at 20° C.	10	18	43	17
Temperature, °C.	7	40	250	70
Duration of run, hours	5	6	4	7
Products, g.:				
Condensable gas	204	173	70	152
Liquid hydrocarbon layer	0	27	15	66
Catalyst layer	43	54	28	45
Hydrogen chloride, carbon dioxide, and loss	75	64	38	59
Distn. of hydrocarbon layer, volume percent:				
Condensable gas	335			62
Liquid fractions:				
Below 40° C.	12			8
Between 40 and 75° C.	30		37	22
Between 75 and 95° C.	7		7	4
Residue	9	9	9	3
Analysis of condensable gas, mole percent:				
Ethane			5.8	
Propane			1.6	2.1
Butane	77.5	79.6	80.2	79.0
Ethyl chloride	21.6	16.6		10.7
Pentane and higher hydrocarbons	0.9	3.8	12.4	8.2

¹ Vapor pres. of isobutane; no nitrogen added.

² Preceded by 2 hours at room temperature.

³ Consists of butane, 22.1; ethyl chloride, 18.0; pentane and higher hydrocarbons, 59.9%.

⁴ Consists of butane, 44.8; ethyl chloride, 25.4; pentane and higher hydrocarbons, 29.8%.

The results given in Table I show that alkylation occurred in good yields at temperature of 40° C. or higher. It is interesting to note that

the liquid product boiled at a relatively low temperature and most of it boiled between 40° and 75° C. with very little boiling above 100° C.

EXAMPLE II

A total of 120 grams of isopropyl chloroformate was added slowly to a glass reactor containing a well stirred mixture of 205 grams of isobutane and 20 grams of aluminum chloride. The reaction temperature was maintained at about the boiling point of isobutane under 1 atmosphere pressure by permitting the isobutane to reflux under a well cooled condenser while the isopropyl chloroformate was introduced gradually to the reaction mixture over a period of 3 hours. Hydrogen chloride was evolved at a moderate rate during the time that the isopropyl chloroformate was added but this evolution became more rapid during an additional 3 hour period of stirring which followed the introduction of all of the isopropyl chloroformate. The increased rate of reaction might have been due to an increase in reaction temperature to about -3° C. which occurred after part of the isobutane had distilled from the reaction mixture during the last part of the stirring treatment. From the reaction product, was obtained 52 grams of colorless liquid hydrocarbon material and 42 grams of used catalyst having the appearance of a reddish brown oil. In addition to the liquid hydrocarbons and catalyst, the recovered materials comprised 148 grams of condensable gases (chiefly isobutane) and 41 grams of a mixture of hydrogen chloride and carbon dioxide. The relatively large loss of 62 grams was probably due to a mechanical loss of hydrogen chloride and carbon dioxide. The condensable gas consisted of 28.5 mole per cent of propane, 67.2% of butane, and 4.3% of pentanes. The 52 grams of colorless liquid hydrocarbon material recovered in this run represent 125% by weight of the propylene which may be considered available from the isopropyl chloroformate. Distillation separated the liquid product into fractions having the boiling ranges and refractive indexes indicated in Table 2.

Table 2.—Distillation of normally liquid hydrocarbon product formed by reaction of isobutane with isopropyl chloroformate in the presence of aluminum chloride

[Charge: 69 cc. (48.7 g.)]

Fraction No.	Boiling range, °C.	Vol. of fraction, cc.	Refractive index @ 20° C.
1	37-51	5.0	1.3692
2	51-75	7.3	1.3762
3	75-83	1.4	1.3818
4	83-96	3.5	1.3885
5	96-127	10.9	1.3974
6	127-152	7.9	1.4067
7	152-177	6.5	1.4164
8	177-200	5.0	1.4261
Residue		5.3	1.4461

From the above table it is to be noted that the product obtained by reacting isobutane with isopropyl chloroformate contained relatively large amounts of hydrocarbons boiling in the range of the pentanes, hexanes, heptanes, octanes, and higher molecular weight paraffinic hydrocarbons of gasoline boiling range.

The foregoing specification and examples indicate the character and practical value of the present invention, although it is not intended that either section should impose undue limitations thereon.

We claim as our invention:

1. A process for synthesizing hydrocarbons which comprises reacting an isoparaffinic hydrocarbon with an alkyl chloroformate under alkylating conditions in the presence of a Friedel-Crafts type metal halide catalyst.

2. A process for synthesizing hydrocarbons which comprises reacting an isoparaffinic hydrocarbon with an alkyl chloroformate at a temperature of from about -20° to about 100° C. in the presence of a Friedel-Crafts type metal halide catalyst.

3. A process for synthesizing hydrocarbons which comprises reacting an isoparaffinic hydrocarbon with an alkyl chloroformate at a temperature of from about -20° to about 100° C. under a pressure of from substantially atmospheric to about 50 atmospheres in the presence of a Friedel-Crafts type metal halide catalyst.

4. A process for synthesizing hydrocarbons which comprises reacting an isoparaffinic hydrocarbon with an alkyl chloroformate under alkylating conditions in the presence of a Friedel-Crafts type metal halide catalyst, while maintaining a molar excess of said isoparaffinic hydrocarbon to said alkyl chloroformate throughout the entire reaction period.

5. A process for synthesizing hydrocarbons which comprises reacting an isoparaffinic hydrocarbon with an alkyl chloroformate at a temperature of from about -20° C. to about 100° C. under a pressure of from substantially atmospheric to about 50 atmospheres in the presence of a Friedel-Crafts type metal halide catalyst while maintaining a molar excess of said isoparaffinic hydrocarbon to said alkyl chloroformate throughout the entire reaction period.

6. A process for synthesizing hydrocarbons which comprises reacting an isoparaffinic hydrocarbon with an alkyl chloroformate under alkylating conditions in the presence of an aluminum halide catalyst.

7. A process for synthesizing hydrocarbons which comprises reacting an isoparaffinic hydrocarbon with an alkyl chloroformate under alkylating conditions in the presence of an aluminum chloride catalyst while maintaining a molar excess of said isoparaffinic hydrocarbon to said alkyl chloroformate throughout the entire reaction period.

8. A process for synthesizing hydrocarbons which comprises reacting an isoparaffinic hydrocarbon with an alkyl chloroformate at a temperature of from about -20° to about 100° C. in the presence of an aluminum chloride catalyst while maintaining a molar excess of said isoparaffinic hydrocarbon to said alkyl chloroformate throughout the entire reaction period.

9. A process for synthesizing hydrocarbons which comprises reacting an isoparaffinic hydrocarbon with an alkyl chloroformate at a temperature of from about -20° to about 100° C. under a pressure of from substantially atmospheric to about 50 atmospheres in the presence of an aluminum chloride catalyst while maintaining a molar excess of said isoparaffinic hydrocarbon to said alkyl chloroformate throughout the entire reaction period.

10. The process of claim 9 further characterized in that said isoparaffinic hydrocarbon comprises isobutane.

11. The process of claim 9 further characterized in that said isoparaffinic hydrocarbon comprises isopentane.

12. A process for synthesizing hydrocarbons

which comprises reacting an isoparaffinic hydrocarbon with an alkyl chloroformate at a temperature of from about -20° to about 100° C. under a pressure of from substantially atmospheric to about 50 atmospheres in the presence of aluminum chloride and another Friedel-Crafts type catalyst while maintaining a molar excess of said isoparaffinic hydrocarbon to said alkyl chloroformate throughout the entire reaction period.

13. A process for synthesizing hydrocarbons which comprises reacting an isoparaffinic hydrocarbon with an alkyl chloroformate at a temperature of from about -20° to about 100° C. under a pressure of from substantially atmospheric to about 50 atmospheres in the presence of a composite comprising essentially aluminum chloride and a refractory carrier while maintaining a molar excess of said isoparaffinic hydrocarbon to said alkyl chloroformate throughout the entire reaction period.

14. A process for synthesizing hydrocarbons of gasoline boiling range and high antiknock value which comprises reacting isobutane with ethyl chloroformate at a temperature of from about 40° to about 100° C. under a pressure of

from substantially atmospheric to about 50 atmospheres in the presence of an aluminum chloride catalyst while maintaining a molar excess of said isobutane to said ethyl chloroformate throughout the entire reaction period.

- 5 15. A process for synthesizing hydrocarbons of gasoline boiling range and high antiknock value which comprises contacting one molecular proportion of ethyl chloroformate and from about 2
10 to about 25 molecular proportions of isobutane with an aluminum chloride catalyst at a temperature of from about 40° to about 100° C. under a pressure of from substantially atmospheric to about 50 atmospheres.
- 15 16. A process for synthesizing hydrocarbons of gasoline boiling range and high antiknock value which comprises contacting one molecular proportion of a propyl chloroformate and from about 2 to about 25 molecular proportions of isobutane with an aluminum chloride catalyst at a temperature of from about -20° to about 100° C. under a pressure of about 50 atmospheres.
